UNITED STATES PATENT OFFICE.

JOHN A. HOPKINS, JR., OF BURNS, KANSAS.

AUTOMATIC FIRE ALARM AND EXTINGUISHER.

1,212,060.

Specification of Letters Patent.

Patented Jan. 9, 1917.

Application filed May 15, 1915. Serial No. 28,411.

To all whom it may concern:

Be it known that I, JOHN A. HOPKINS, Jr., a citizen of the United States, residing at Burns, in the county of Butler and State of Kansas, have invented certain new and useful Improvements in Automatic Fire Alarms and Extinguishers; and I do hereby declare the following to be a full, clear, and exact description of the invention, such as will enable others skilled in the art to which it appertains to make and use the same.

The invention relates to an automatic fire alarm and extinguisher.

The object of the present invention is to improve the construction of fire alarms and to provide an automatic fire alarm and extinguisher of simple and comparatively inexpensive construction adapted to sound an audible alarm and capable also of inverting a fire extinguisher and discharging the contents thereof for extinguishing a fire.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings Figure 1 is a side elevation of a fire alarm and extinguisher constructed in accordance with this invention, Fig. 2 is a vertical sectional view of a portion of the device, Fig. 3 is a sectional view of the lower portion of the tubular casing illustrating the arrangement of the hollow fusible plug, Fig. 4 is a transverse sectional view on the line 4—4 of Fig. 2, Fig. 5 is a detail view illustrating the arrangement of the fixed and movable contacts, Fig. 6 is a side elevation of the tubular casing, Fig. 7 is a detail view of the washer which forms a bearing for the upper end of the coiled spring, Fig. 8 is a detail perspective view of the hollow fusible plug, Fig. 9 is a detail view of the frame to which the fire extinguisher is pivoted. Fig. 10 is a horizontal section through the tubular casing on a plane a short distance above the washer.

Like numerals of reference designate corresponding parts in all the figures of the drawings.

In the accompanying drawings in which is

illustrated the preferred embodiment of the invention, 1 designates a tubular casing constructed of suitable metal and having a lower tapered portion 2 and an open lower end 3. The lower portion of the casing is also provided with perforations 4 and is adapted to receive a hollow fusible plug 5' tapered to conform to the configuration of the tapered portion of the casing and constructed of a material adapted to melt at a low point so that it will easily fuse or melt in the event of a fire occurring in the locality of the casing. The open lower end is adapted to expose the fusible plug to the action of the heat of a fire and the perforations which are also provided for this purpose permit the escape of the melted material of which the plug is made. Any suitable material such as cocoa butter may be employed in the manufacture of the plug and the hollow character of the plug will enable the same to collapse readily when it is subjected to the heat of a fire. The fusible plug is adapted to hold a coiled spring 5 in a retracted or compressed condition and the said coil spring 5 is interposed between the upper end of the fusible plug and a washer 6 which is arranged in a horizontal slot 7 in the upper portion of the casing 1. The coil spring 5 which is equipped at its lower end with a cylindrical cap 8 of any suitable material is also provided with a longitudinal stem 9 consisting of an extension of the lower end 10 of the coil spring and extending entirely through and above the same as clearly illustrated in Fig. 2 of the drawings. The washer 6 which is removably arranged in the horizontal slot 7 of the casing 1 is provided with a radially arranged slot 11, having its inner portion enlarged at 12 and forming a passage for the stem 9 of the coiled spring. The washer is adapted to be readily removed to permit the spring to be detached when it is necessary to replace the fusible plug, after an operation of the device.

The casing 1 is provided at opposite sides of its intermediate portion with laterally projecting ears or flanges 13 adapted to receive screws or other suitable fastening devices for securing the casing to a wall or other supporting surface and the upper end of the casing is secured to the wall by a screw 14 which also fastens a fixed contact 15 to the upper portion of the casing which is extended at the back 16.

The fixed contact 15 which is insulated by

washers 17 of mica or any other suitable material, receives one of the wires 18 of a closed circuit which has its wire 19 connected with the upper portion of the stem 9 which constitutes a movable contact. The upper end 20 of the stem 9 is split or bifurcated and extends into a recess 21 in the fixed contact 15. The terminal of the wire 19 is secured to a flange 21^a of the stem and when the latter is carried downwardly through the expansion of the spring incident to the melting of the fusible plug the upper end 21^b of the stem will be carried out of the recess 21 of the fixed contact 15 and the circuit will be broken. The closed circuit may control any suitable audible alarm which will be sounded when the circuit is broken by the downward movement of the stem 9. The stem 9 is also provided at its upper portion with a shoulder 22 which engages the inner arm 23 of the trigger 24 and holds the same in engagement with the recess 25 of a link or bar 26, of a pivotally mounted fire extinguisher 27. The trigger 24 which is approximately L-shaped is pivoted at a point intermediate of the ends of its longer side at 28 in a slot 29 in one side of the casing 1. The arm or bar 26 is supported upon the washer 6 which has a projecting portion to facilitate its removal. The supported end of the arm or bar 26 extends into the slot 29 and the recess 25 is formed in the upper edge of the arm or bar and it receives the short side of the L-shaped trigger which projects downwardly as clearly shown in Fig. 2 of the drawings. The supported arm 23 of the trigger is heavier than the L-shaped arm or portion which engages the recess and when the spring and the stem with its shoulder 22 moves downwardly, the trigger will be released and will disengage itself by gravity from the recess 25. Should, however, the trigger remain in engagement with the recess it will be positively carried out of such engagement by the shoulder 22 of the flange to which the wire 19 is connected. The fire extinguisher 27 which is supported in an inclined position to cause it to drop by gravity when released is provided at its upper side with an ear 30 to which the arm or bar 26 is connected by a pivot 31, but the arm or bar may be secured to the fire extinguisher in any other desired manner.

The fire extinguisher 27 which has a caved lower end is provided thereat with spaced ears 32 and it is pivoted by a horizontal fastening device 33 to an open frame 34 preferably constructed of a single piece of metal and bent into approximately triangular shape as clearly illustrated in Fig. 9 of the drawings. The fastening device 33 which may consist of a long nail is adapted to project beyond the frame and be embedded in the adjacent wall to which the casing 1 is secured. The fire extinguisher

which may be of desired construction is preferably equipped at the upper portion with a receptacle 35 arranged in a vertical position when the fire extinguisher is in its normal inclined position and depending from the top of the fire extinguisher and provided interiorly thereof with perforations 36 forming outlet apertures for the discharge of an acid to produce the fire extinguishing fumes or gases when the fire extinguisher is released and dropped to a depending vertical position through the operation of the device. The fire extinguisher is provided with a nozzle 37 having discharge apertures 38 and connected with the fire extinguisher by a neck 39 adapted to receive a plug of fusible material to form a stopper for retaining the contents of the extinguisher within the same until it is fused by the heat of the fire.

This will prevent evaporation of the contents of the fire extinguisher and loss of strength of the same.

When a fire occurs the heat will melt the fusible plug 5' and permit the spring to expand and move its stem downwardly. This will open the closed circuit and sound the audible alarm and at the same time release the fire extinguisher and cause the same to swing downwardly to discharge its contents. By mounting the supporting frame of the fire extinguisher above the floor, the fire extinguisher will hang in a depending vertical position when released by the trigger. The fire extinguisher is set at an inclination and it will positively swing downwardly when released.

What is claimed is:—

1. A device of the class described including a tubular casing adapted to receive a fusible plug, a coiled spring arranged within the casing and having one of its ends arranged to be engaged by the plug, said spring being provided with a stem extending from such end of the spring through the latter and projecting beyond the other end of the spring, a removable washer mounted within the casing and having a slot receiving the said stem and constituting a bearing for the adjacent end of the spring.

2. A device of the class described including a tubular casing adapted to receive a fusible plug within one end of it, a contact located at the other end of the casing, a spring arranged within the casing and having one of its ends bearing against the fusible plug and provided with a stem extending from such end to the spring and normally engaging the said contact, said stem constituting a movable contact and means for holding the other end of the spring.

3. A device of the class described including a casing adapted to receive a fusible plug, a spring mounted within the casing and arranged to be held in a compressed con-

dition by the fusible plug, a fixed contact provided with a recess and a stem connected with the spring and having a bifurcated portion engaging the fixed contact in the recess thereof and constituting a movable contact adapted to be carried out of such engagement by the expansion of the spring.

5 4. A device of the class described including an inclined fire extinguisher pivotally mounted at its lower end, an arm or bar connected with the fire extinguisher and provided with a recess, a casing receiving the arm or bar and supporting the same, said casing being adapted to contain a fusible 10 plug, a spring located within the casing and arranged to be maintained in a compressed condition by the fusible plug and a trigger connected with the spring and normally engaging the arm or bar and adapted to release 15 the same when the spring expands.

20 5. A device of the class described including a pivotally mounted inclined fire extinguisher provided at the top with a vertically disposed receptacle having apertures at its upper portion and means including a fusible plug for normally holding the fire extinguisher in an inclined position.

25 6. A device of the class described including a casing having a lower portion provided with apertures and adapted to receive a fusible plug, a coiled spring located within the casing and arranged to be held in a compressed condition by the fusible plug, a

30 stem connected with the lower end of the spring and extending through the same and constituting a movable contact, a relatively fixed contact arranged to coact with the stem, an automatically tilttable fire extinguisher and a catch for holding the fire extinguisher normally against movement, said catch being 35 connected with the stem and adapted to be operated to release the fire extinguisher when the spring expands.

40 7. A device of the class described including a tubular casing provided at one end 45 with apertures and adapted to receive a fusible plug, a coiled spring located within the casing and arranged to be maintained in a compressed condition by the fusible plug and expansible when the plug is fused, a 50 rod connected with the spring and adapted to be actuated by the same and constituting a movable contact, a fixed contact arranged in the path of the rod, a catch connected with the rod and actuated by the same and an 55 automatic tilttable fire extinguisher provided with a bar or member engaged by the catch for holding the fire extinguisher normally against movement, said bar or member being released by the movement of the spring. 60

In testimony whereof I affix my signature in presence of two witnesses.
